UNITED STATES PATENT OFFICE.

EDWARD B. HESS, OF BROOKLYN, AND LEWIS C. MYERS, OF FREEPORT, NEW YORK,
ASSIGNORS TO ROYAL TYPEWRITER COMPANY, INC., OF NEW YORK, N. Y., A COR-
PORATION OF NEW YORK.

TYPEWRITING MACHINE.

Original application filed May 11, 1920, Serial No. 380,601. Divided and this application filed June 19,
1922. Serial No. 569,322.

To all whom it may concern:

Be it known that we, EDWARD B. HESS and LEWIS C. MYERS, citizens of the United States of America, and residents, respectively, of the borough of Brooklyn, city of New York, county of Kings, and State of New York, and Freeport, county of Nassau, and State of New York, have invented certain new and useful Improvements in Typewriting Machines, of which the following is a specification.

The present invention relates generally to typewriting machines and has more particularly reference to the construction of the ball raceway associated with the transversely movable carriage, particularly though not exclusively, susceptible of use in connection with the construction of Royal typewriter shown in application Ser. No. 380,601 filed May 11, 1920, of which the present application is a division.

The main object and feature of the invention is to prevent the accumulation of particles of foreign matter upon the bearing surfaces of the longitudinal grooves of the raceway, and the invention consists of the features of construction and arrangement of parts hereinafter disclosed.

In the accompanying drawings the invention is disclosed in a concrete and preferred form in which—

Fig. 1 is a view in end elevation of a transversely movable typewriter carriage and its supporting means, with parts omitted for the sake of clearness.

Fig. 2 is a vertical sectional view of the lower raceway.

Figure 3 is a plan view of the lower raceway and adjacent parts.

In the particular embodiment of the invention here disclosed 1 indicates a suitable framework having lower raceway 4 in which slides the reciprocating carriage 7 having upper raceway 2. Interposed between the upper and lower raceway are the usual balls 62 having encircling gears 63 meshing with racks 64 and 65 on the upper and lower raceways respectively. In con-

nection with the construction of the upper and lower raceways it is to be noted that the shape of the longitudinal grooves with which balls 62 engage is unusual in that the grooves are provided with longitudinally extending raised portions 66 and a central gutter 67. The advantage of this construction, especially in connection with the lower raceway, is that dust or foreign particles of matter will not accumulate on surfaces 66 but will work into gutter 67 with which balls 62 are not in engagement thereby greatly facilitating smooth action of the parts.

Another advantage of this construction is that the raceways may be more quickly finished than heretofore, on account of the fact that when grinding the hardened steel, of which these raceways are made, the surfaces 66 to be finished are narrower than heretofore, by reason of the presence of gutter 67 and therefore the work can be done more quickly and accurately.

We claim:

1. In a typewriting machine: an upper and a lower ball raceway having longitudinal grooves, the groove of the lower raceway having a central gutter and a longitudinally extending raised portion on each side of the gutter, rack teeth disposed on the opposite longitudinal edges of the raceways, and balls having encircling gears interposed between said raceways.

2. In a typewriting machine: an upper and a lower ball raceway having longitudinal grooves, the grooves of said raceways having each a central gutter and a longitudinally extending raised portion on each side of the gutter, rack teeth disposed on the opposite longitudinal edges of the raceways, and balls having encircling gears interposed between said raceways.

Signed at New York city in the borough of Manhattan, county and State of New York, this 26th day of May, 1922.

EDWARD B. HESS.
LEWIS C. MYERS.
